UNITED STATES PATENT OFFICE.

JEREMIAH A. SCRIVEN, OF NEW YORK, N. Y.

DRAWERS.

SPECIFICATION forming part of Letters Patent No. 597,747, dated January 25, 1898.

Application filed September 24, 1897. Serial No. 652,832. (No model.)

To all whom it may concern:

Be it known that I, JEREMIAH A. SCRIVEN, a resident of the city, county, and State of New York, have invented an Improvement 5 in Nether Garments, of which the following is a full, clear, and exact description.

My invention relates to nether garments, and has for its object to produce a nether garment, either drawers or trousers or pants, 10 wherein the strain upon the seat and crotch portions incident to the wearer's sitting down will be compensated for in a very efficient manner.

To this end my invention consists in the 15 construction of nether garments hereinafter set forth and claimed.

In the accompanying drawings, Figure 1 is a front view of a nether garment embodying my invention. Fig. 2 is a fragmentary view 20 thereof, showing the mode of inserting the elastic insertion.

In the drawings, A A are the inelastic back sections of the garment, and A' A' the inelastic front sections, which sections are united together at their edges a b c in any suitable manner. Interposed between the upper parts of the rear sections A is an elastic insertion d, which is in the form of a strip and extends downward into and through the crotch and 25 upward into the front opening of the crotch, forming the lower edge e of the said opening. In the seat portion of the garment adjacent to and immediately in rear of the crotch-seams f, uniting the front and rear sections, is a 30 narrow elastic insertion g g, which extends up on each side of the elastic strip d and is in one piece therewith. The elastic insertion g g fills cut-away portions of the rear sections 35 of the garment at this point and is stitched to the edges h of the said cuts or openings, which are preferably V-shaped. By referring 40 to Fig. 1 it will be noticed that the insertion g g extends laterally of the length of the garment in the rear of the crotch portion and is 45 just below the place where the lower parts of

the buttocks of a wearer of the drawers terminate and the legs begin.

When the wearer is standing, the under-garment is in the position shown in Fig. 1 and there will be a minimum amount of strain 50 thereon; but when the wearer of the garment sits down the garment will be stretched across his buttocks and the strain will be brought to bear upon the elastic insertions.

The front edges i of the front opening of 55 the garment are brought down and sewed to the elastic insertion d at or near its upper front edge e, which constitutes the lower edge of the crotch. The insertions d and g g are described herein as "elastic," and by that 60 term I mean to imply that they are more elastic than the remaining portions of the garment, which for the purpose of convenience I herein designate as being "inelastic;" but such term is to be understood as meaning that 65 the portions referred to are less elastic than the more elastic insertions and gussets.

I am aware that it is not new to put insertions in the crotch-seams f of the garment. Such, however, I do not claim; but 70

What I do claim, and desire to secure by Letters Patent, is—

An undergarment comprising inelastic front and rear sections secured together at the crotch, an elastic insertion d in the form of 75 a strip uniting the rear sections together and extending downward into and through the crotch and upward into the front opening of the crotch forming the lower edge e of the said opening and a narrow elastic insertion 80 g g adjacent to and immediately in rear of the crotch-seam, the said insertion being upon each side of the elastic strip and in one piece therewith, substantially as described and for the purposes set forth.

JEREMIAH A. SCRIVEN.
